CLAIM

The ornamental design for a SPECT/CT imaging scanner, as shown and described.

DESCRIPTION

FIG. 1 is a first perspective view of the SPECT/CT imaging scanner.

FIG. 2 is a second perspective view of the SPECT/CT imaging scanner.

FIG. 3 is a first side view of the SPECT/CT imaging scanner.

FIG. 4 is a second side view of the SPECT/CT imaging scanner.

FIG. 5 is a top view of the SPECT/CT imaging scanner.

FIG. 6 is a bottom view of the SPECT/CT imaging scanner.

FIG. 7 is a front view of the SPECT/CT imaging scanner.

FIG. 8 is a back view of the SPECT/CT imaging scanner; and,

FIG. 9 is a front view along line 9-9 of the SPECT/CT imaging scanner.

The even length broken lines are included for the purpose of illustrating portions of the SPECT/CT imaging scanner that form no part of the claimed design. The alternating length broken lines illustrate the bounds of the claimed design, and form no part thereof.
